UNITED STATES PATENT OFFICE

2,445,080

WEB ROLL SUPPORT

Charles H. Petskeyes, Davenport, Iowa, assignor
to Gellman Manufacturing Company, Rock
Island, Ill., a corporation of Illinois

Application June 9, 1945, Serial No. 598,470

1 Claim. (Cl. 242—68)

1

This invention relates to certain novel improvements in web roll supports and more particularly the invention is concerned with and relates to an arrangement for preventing the overriding or backslashing of a roll of paper during the wrapping operation of the machine.

In this aspect of the invention, the primary object is to provide an arrangement capable of these accomplishments, which will be economical in manufacture, highly efficient in use, and simple in construction, an arrangement which can be manipulated with safety and ease when mounting a roll of paper in position with respect to the wrapping mechanism.

Another object of the invention of equal importance is the provision of a core for each end of the roll of paper in which core is incorporated frictional means for preventing overriding or backslashing of the roll of paper and which core, while being capable of these accomplishments may nevertheless be inserted in the end of the roll of paper in the conventional manner. This latter feature permits the use of standardized rolls of paper.

The present invention is intended to be used in connection with a bread wrapping machine such as that disclosed in United States Patent Nos. 2,276,590; 2,252,028; 2,235,503; 2,232,558 and 2,230,797.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary perspective view of a bread wrapping machine showing my improvements incorporated therein;

Fig. 2 is a vertical sectional detail view of the paper roll mounting core block embodied in the invention.

The drawings illustrate the preferred form of construction by which the several objects of my invention are accomplished.

The conventional bread wrapping machine, as is evident from the several patents hereinbefore referred to, comprises side frame members 10 and 11 housing the bread conveying and wrapping mechanism, the latter not being shown in the drawings of this application, as such mechanism does not constitute any part of the present invention.

Associated with these frames 10 and 11 are one or more screw shafts 12, each having a suitable

2

hand wheel 13 to facilitate rotation of these shafts. Extending parallel with these shafts 12, between the frames 10 and 11, are stabilizer bars 14.

Spaced bracket elements are indicated at 15, and these bracket elements are provided with enlarged bearings 16 at their inner end portions through which the screw shafts 12 work. These bracket elements also provide depending feet 17 bifurcated as at 18 to provide a seat engageable with the stabilizer bars 14. The bracket elements 15 extend outwardly from the side frames 10 and 11, as at 19, and the extremities of these portions 19 provide bearings 20.

Associated with each of these bearings 20 is a stud shaft 21 having a reduced portion 22 bearing threads 23 for threaded engagement with a nut 24. The reduced portion 22 of the stud shaft 21 projects through a mounting disc 25 having fixed connection with the bearing 20 by means of a pin 26. Secured to the outer face 27 of this mounting disc 25 is a friction ring 28 formed of fiber or other suitable friction material.

The stud shaft 21 has an enlarged portion 29 which bears against the mounting disc 25. This enlarged portion 29 projects through an opening 30 formed in a core or plug 31 in which opening there may be positioned a suitable bushing. The enlarged portion 29 of the stud 21 has a head portion 32 which fits into a socket 33 formed in the plug 31. The plug 31 is freely rotatable upon the enlarged portion 29 of the stud shaft 21 and provides an internal flange 34 riding within an opening 35 formed in the friction ring 28.

The medial circumferential surface 37 of the plug 31 provides a tapered shoulder 38 which is adapted to engage the rim of the bore 39 through the roll of paper 39.

The plug 31 in its outer portion provides a recess or socket portion 40 into which fits the mounting disc 25 and the friction ring 28 in a manner such that opposing faces of the ring 28 and the plug 31, as indicated at 42, will have frictional engagement with respect to each other.

In bread wrapping machines of the type illustrated in the aforementioned patents, the paper roll 39 is intermittently rotated by a mechanism which exposes successively, sections of the web 43 of the roll 39 in the area of the wrapping operation. Mechanism of this type has a tendency to cause the roll to rotate suddenly and end with a slight jerk. In so acting, the paper roll 39 often overrides the intended degree of rotation of the paper roll and, as a result, considerable

slackness results and much of the web of the paper is unrolled from the roll. This overriding and, in fact, any backlashing of the roll, is prevented by reason of the engaging surfaces of the plug 31 and the friction ring 28, with the result that overriding or backlashing of the roll is prevented. In this manner I have provided a means for stabilizing the rotation of the roll of paper in a manner best suited for the intended purpose. The simplicity of the invention is self-evident from the foregoing description.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

5 A mounting core for a roll of paper comprising a non-rotating stud shaft, a mounting disc, means carrying said stud shaft and having connection with said mounting disc to prevent rotation of said mounting disc relative to said shaft, a paper roll supporting core mounted on said stud shaft and having a socket portion, a friction disc mounted in said socket and supported by said core and adapted to have facial engagement with 10 said mounting disc, substantially as described.

CHARLES H. PETSKEYES.
